INVENTOR

UNITED STATES PATENT OFFICE.

SAMUEL D. ROSENFELT, OF CHICAGO, ILLINOIS, ASSIGNOR TO FRANKLIN RAILWAY SUPPLY COMPANY, OF WILMINGTON, DELAWARE, A CORPORATION OF DELAWARE.

FIRE-DOOR DEVICE.

1,171,463.

Specification of Letters Patent.

Patented Feb. 15, 1916.

Application filed August 11, 1914. Serial No. 856,224.

To all whom it may concern:

Be it known that I, SAMUEL D. ROSENFELT, a citizen of the United States, and a resident of Chicago, in the county of Cook 5 and State of Illinois, have invented a certain new and useful Improvement in Fire-Door Devices, of which improvement the following is a specification.

This invention relates to apparatus for 10 operating fire doors of locomotive boilers or other furnaces, and more particularly such form of apparatus wherein the doors are pivoted to swing laterally and vertically, and a fluid pressure cylinder and piston are 15 employed to actuate the same, as shown in the prior application of Albert G. Elvin and myself, Serial No. 789,645, filed September 13, 1913, and the prior Patent No. 1,031,379, dated July 2, 1912.

20 My present invention has for its object to provide an improved manually operative means for actuating the doors independently of the fluid pressure mechanism whenever desired.

25 In the accompanying drawings: Figure 1 is a front elevation of a fire door apparatus embodying my improvement; Fig. 2, a side or end view, the lower portion of the doors being broken away; Fig. 3, a longitudinal 30 section taken on the axis of the pivot pin of one of the doors and showing the hand operating lever connections; and Fig. 4, a horizontal section through the fluid pressure cylinder and piston.

35 According to the construction shown in the drawing, my invention is illustrated as applied to a locomotive boiler having a door frame, 1, suitably mounted on the back head, 2, and surrounding the fire door, 40 opening which is covered by a pair of doors, 10 and 11, pivoted upon suitable pins to swing laterally and vertically. The pivot pins, 6 and 7, may be rigidly mounted at their ends in the upper portion of the frame, 1, and serve also to support the motor cylinder, 4, by means of the depending flange or web, 4^a.

The pivoted arms of the doors, 10 and 11, are provided with the respective gear segments, 12 and 13, which mesh together, and both doors are thus opened by means of the link, 14, pivotally attached at one end to the lug, 12^a, and at the other end to a pin, 15, carried by the piston, 6, and extending 55 through a horizontal slot in the side of the

motor cylinder, 4. One end of the cylinder is closed by the cap, 5, and the piston is operated by fluid pressure admitted through pipe 24, and controlled by a suitable valve.

When the operator desires to open the 60 furnace doors for firing, or other purposes, he opens the valve, thereby admitting fluid into the cylinder, where it acts on the piston, 6, moving the same to the right, and, through the connecting link and segmental 65 gears, swings the doors upward on their pivots to the open position, in which the doors remain as long as the valve is held open. When the valve is released and closed, the fluid exhausts from the cylinder, 70 and the doors close by gravity.

For operating the door or doors by hand, I provide a hand lever, 18, which may be mounted on one of the door pivot pins, 7, which is made long for this purpose, the pin being 75 formed with a shoulder portion between the frame, 1, and the web, 4^a, on which portion the door, 11, is pivotally mounted, and carrying a bushing, 16, between the web and the nut at the end of the pin. On the bushing, 16, is rotatably mounted a rocker arm, 19, having an extension, 21, provided with an elongated slot through which extends the hand lever, 18, which is also pivotally mounted 80 on the bushing, 16. A spring actuated plunger, 22, is mounted within a recess in the rocker arm, and bears against the hand lever, 18, to normally push the same toward the outer end of the slot in the extension, 21, of the rocker arm. 85 The rocker arm is also provided with a projection, 26, for engaging a lug, 17, on the door, 11, in order to open the same when the rocker arm is turned by the hand lever. When the nut at the end of the pin is screwed up, the parts are secured 90 in their respective positions, the bushing, 16, being clamped against the web, 4^a, which bears against the shoulder of the pin, leaving the door, rocker arm and lever free to turn on their pivots.

In order to hold the door at different positions, a latch plate, 20, may be suitably supported at the front of the cylinder, and be provided with notches such as 23, 27, and 25, for receiving the hand lever, 18. When the 105 door is closed, the lever normally occupies the upper notch, 23, and when the door is fully opened, the lever is set in the lower notch, 25, but when it is desired to only slightly or partially open the door, the lever 110

is set in the intermediate notch, 27, known as the "smoke latch", for admitting air over the fire at certain periods to eliminate smoke.

5 The hand lever normally extends upward at an angle to the horizontal when the door is closed, and when released from the notch, 23, the spring plunger, 22, tends to throw the lever outward to clear the edge of the 10 latch plate, 20, whereupon the lever may be turned downward to the desired position, the rocker arm being also actuated by this movement, and engaging the lug, 17, to swing the doors, 11 and 10, through their 15 connecting gears, 12 and 13. The hand lever mechanism does not interfere with the operation of the doors by fluid pressure at any time desired, as the lug, 17, merely moves away from the projection, 26, on the 20 rocker arm when fluid pressure is admitted to the motor cylinder to open the doors.

Having now described my invention, what I claim as new and desire to secure by Letters Patent is:

25 1. In a fire door apparatus, the combination of a door, a pivotally mounted member for actuating the same, and a hand lever for operating said member and also having a limited longitudinal movement relative 30 thereto.

2. In a fire door apparatus, the combination of a door, a pivotally mounted member for actuating the same, and a hand lever also mounted on said pivot and having a 35 loose connection with said member permitting a limited longitudinal movement relative thereto.

3. In a fire door apparatus, the combination of a vertically movable door, a pivotally 40 mounted member for actuating the same, a hand lever mounted to turn with said member but having a limited longitudinal movement relative thereto, and a latch plate having notches to be engaged by said lever.

45 4. In a fire door apparatus, the combina-

tion of a door pivoted at its upper side to swing laterally and vertically, a rocker member mounted on said pivot for actuating said door, and a hand lever mounted to turn with said rocker but having a limited longitudinal movement relative thereto. 50

5. In a fire door apparatus, the combination of a door pivoted at its upper side to swing laterally and vertically, a rocker member mounted on said pivot for actuating said door, and a hand lever also mounted on said pivot and having a loose connection with said rocker permitting a limited longitudinal movement. 55

6. In a fire door apparatus, the combination of a door, a pivot pin for said door, a rocker arm mounted on said pin and having a projection for actuating said door, and a hand lever mounted on said pin to turn with said rocker but having a limited longitudinal 60 movement relative thereto.

7. In a fire door apparatus, the combination of a door, a pivot pin for said door, a rocker arm mounted on said pin and having a projection for actuating said door, a hand 70 lever mounted on said pin and to turn with said rocker but having a limited longitudinal movement relative thereto, and a spring device on said rocker bearing against the lever. 75

8. In a fire door apparatus, the combination of a door frame, a pivot pin rigidly mounted therein and having a shoulder, a door mounted to swing on the shoulder portion of said pin, a motor cylinder having a 80 flange supported on said pin outside the shoulder, a bushing on the pin outside the flange, a hand lever device rotatably mounted on said bushing, and a nut for clamping the bushing against the cylinder flange.

SAMUEL D. ROSENFELT.
